UNITED STATES PATENT OFFICE.

JOSEPHINE M. RISSELT, OF TENAFLY, NEW JERSEY.

ABDOMINAL SUPPORT.

Application filed April 9, 1925. Serial No. 21,897.

This invention relates to body supports, and more particularly to supports for maintaining the abdominal muscles in position.

Heretofore abdominal belts have been constructed in such a manner that they either required thigh straps for retaining the belt in position, with great discomfort to the wearer, or they were so tightly fitted to prevent displacement as to cause irritation and inconvenience to the perineum. Furthermore, the construction of such belts required application of the same while the user was in standing position and when the abdomen was projected downwardly and outwardly. The usual binding straps were then necessarily employed in attempting to raise the muscles at the region of the perineum. In such a case the straps were drawn so tightly that too great a pressure was applied to the lumbar muscles without effectually replacing the abdomen.

It is an object of the present invention to provide an abdominal support which may be applied to the body of a person while in a reclining position and when the abdomen has assumed its more natural position, thus eliminating the necessity of exerting any strap pressure to force the regions of the perineum in position.

Another object of the invention is the provision of an abdominal belt having regions of rigidity disposed longitudinally of the abdomen, with transverse straps above and below the rigid portions, which straps when drawn comfortably taut will not only form an efficient support for retaining the abdomen in position, but by reason of the inward flexing of the less rigid portions of the belt, where the straps are connected, will prevent displacement of the belt and permit of adjustment for the proper expansion of abdominal regions at the upper end of said belt.

A further object of the invention is the provision of a one-piece belt made of light-weight materials and designed in such a manner that a patient or wearer may step into the same and adjust a securing strap or straps by a pull and sliding movement when the patient is lying on his back, the device being adapted not only as a belt to support the abdomen but for the relief in ruptures, sprained backs, for reducing, for use on a patient after certain types of operations, and for incorporation in corsets and brassières.

With the above recited and other objects in view, the invention resides in the novel construction set forth in the following specification, particularly pointed out in the appended claims and illustrated in the accompanying drawings, it being understood that the right is reserved to embodiments other than those actually illustrated herein, to the full extent indicated by the general meaning of the terms in which the claims are expressed.

In the drawings—

Figure 1 is a side view of my abdominal belt shown applied to a patient;

Fig. 2 is a rear view of the belt as applied;

Fig. 3 is a plan view of the belt in open position;

Fig. 4 is a transverse vertical section taken along the line 4—4 of Fig. 3;

Fig. 5 shows the vertical section of Figure 4 when the belt has been applied.

Fig. 6 is a similar section taken along the line 6—6 of Fig. 3.

Referring more particularly to the drawings, 10 designates the front portion of the belt, which is reinforced at its upper and lower edges by means of a braid 11. At the lower end is provided a depending triangularly shaped projection 12, and directly opposite this projection is formed a cut-out or depressed portion 13.

A pair of end portions 14 and 15 are connected to the opposite ends of the front portion by means of elastic fabric 16. The end portions are reinforced along their upper and lower edges by means of braid 17. The upper end of each end portion is extended upwardly as shown at 18 in order to provide sufficient garment to engage neatly beneath the shoulders and points above the lumbar muscles of the back. The vertical edges of the end portions are reinforced by resilient stays 19 in order to form sufficient stiffening for the outer ends of the end portions to prevent folding of the same. A tab is formed of a single piece of material, as shown at 20, or of a strap folded upon itself, shown at 21, and secured to either an upper or a lower end of the outer edges of the end portions 14 and 15. Straps 22 are secured to the upper tabs, while straps 23 are secured to the lower tabs and are provided with some form of buckle 24 at the free ends for receiving the free ends of either a strap 25

or 26, as the case may be, depending upon the relative positions of the buckles and said straps. A strap 25 is secured, as shown at 37, to the front portion adjacent its upper edge and beyond the ends of the plurality of resilient stays 28. The strap 26 is secured intermediate its ends, as shown at 29, to the downwardly projecting portion 12 of the front member of the belt and below the free ends of the resilient stays 28. A reinforcing leather plate 30 is secured to the front member 10 across the strap 26 where said strap is secured to the front member and across the lower ends of the stays 28.

15 Other reinforcing stays such as 31 and 32 are secured to the front member 10 adjacent its ends. The frame portion 10 and the end portions 14 and 15 are made of fabric and are therefore flexible.

20 A strap 33 has its opposite ends secured to the opposite edges of the front member 10 and adjacent each end of said front member, and is adapted to provide a guide for the free ends of the straps 25 and 26. A strap 34, which is shorter than either of the straps 33, is secured to each inner end of the end members 14 and 15 and is likewise adapted to receive the free ends of the strap 25 and not only aid in guiding the strap but 30 maintain the strap in its elevated position.

A free end of the strap 25 at one end of the belt is adapted to be received by a buckle 24 at the opposite end of the belt, while a free end of the strap 26 at one end of the belt is adapted to be received by a buckle 24 located at the opposite end of the belt. In this condition of the belt, the patient may step directly into the same and slide it into position in the region of the lumbar muscles 35 of the back. It also must be borne in mind that since the straps 25 and 26 are engaged by their respective buckles 24 at the sides of the body, the patient is not required to stand in order to apply the same, and, further-

40 more, the belt may be applied by lying flat on the back and when the muscles of the abdomen are in proper position. Furthermore, the guides 34 and 33 permit the free ends of the straps to be readily drawn taut by a 45 pull and sliding movement. It will also be borne in mind that the straps 25 and 26 are secured at their middle points to the front member 10 of the belt and beyond the free end of the resilient stays 28 which normally 50 support the abdominal muscles, so that when the strap 26 is drawn taut the flexible edge 12 of the front member of the belt will be drawn inwardly and form a rest or support for the abdomen. The strap 25 is likewise 55 secured to a portion of the belt which is free of stays so that the same may be properly adjusted to permit the proper expansion of the body and without any inconvenience 60 to the wearer.

Referring to Figure 3, the left hand end 65 of strap 25 is passed through tab 21 and connected to the buckle 24 on strap 22 at the right of the garment while the right hand end of strap 25 is carried around the back of the wearer and secured to the buckle on 70 the strap 22 of tab 21 at the left of the garment. Similarly the right hand end of strap 26 is passed through the adjacent tab 21 and connected to the left hand buckle on strap 23 while the left hand end of strap 26 is secured at the back of the wearer to the buckle on strap 23 at the right of the garment. 75

What I claim is:—

1. An abdominal belt comprising a strip 80 of fabricated material, resilient stays secured transversely to and centrally of the strip, the ends of the stays being spaced from the adjacent edges of the strip, a strap secured intermediate its ends at each edge of the 85 strip beyond the ends of the stays, and guides receiving the free ends of the straps to permit sliding of said straps during application of the belt, said stays being spaced a greater distance apart at the upper ends 90 than at the lower ends thereof.

2. An abdominal belt comprising a front portion and end portions made of fabricated material, elastic members connecting the end portions with the front portion, resilient 95 stays secured centrally of the front portion and terminating short of the upper and lower edges of said portion, a flexible plate embracing the lower ends of the stays, the upper ends of the stays being spaced a 100 greater distance apart than the lower ends, straps connected intermediate their ends to the front portion and beyond the opposite ends of the resilient stays, other resilient stays secured to the front portion adjacent 105 the ends thereof, and resilient stays secured to the end portions for reinforcing said portions.

3. An abdominal belt comprising a front portion and end portions made of fabricated 110 material, elastic members connecting the end portions with the front portion, resilient stays secured centrally of the front portion and terminating short of the upper and lower edges of said portion, straps connected intermediate their ends to the front portion and beyond the opposite ends of the resilient stays, guides for retaining the respective straps in position adjacent an edge 115 of the front and end portions and permitting sliding movement of the free ends of the straps during adjustment, and spaced straps connected to the ends of the end portions and provided with securing means coacting 120 with the free ends of the first-mentioned 125 straps for tightening said straps.
